US00D834194S

(12) **United States Design Patent** (10) **Patent No.:** **US D834,194 S**
Blain et al. (45) **Date of Patent:** **** Nov. 20, 2018**

(54) **INTERBODY BONE IMPLANT**

(71) Applicant: **Spinal Elements, Inc.**, Carlsbad, CA (US)

(72) Inventors: **Jason Blain**, Encinitas, CA (US); **Greg Martin**, Encinitas, CA (US)

(73) Assignee: **Spinal Elements, Inc.**, Carlsbad, CA (US)

(**) Term: **15 Years**

(21) Appl. No.: **29/632,794**

(22) Filed: **Jan. 10, 2018**

Related U.S. Application Data

(60) Continuation of application No. 29/602,768, filed on May 3, 2017, now Pat. No. Des. 810,942, which is a continuation of application No. 29/562,284, filed on Apr. 25, 2016, now Pat. No. Des. 790,062, which is a continuation of application No. 29/537,496, filed on Aug. 26, 2015, now Pat. No. Des. 765,854, which is a division of application No. 29/404,921, filed on Oct. 26, 2011, now Pat. No. Des. 739,935.

(57) **CLAIM**

The ornamental design for an interbody bone implant, as shown and described.

DESCRIPTION

FIG. 1 is a front perspective view of an interbody bone implant according to an embodiment;

FIG. 2 is a top view of the interbody bone implant illustrated in FIG. 1;

FIG. 3 is a bottom view of the interbody bone implant illustrated in FIG. 1;

FIG. 4 is a first side view of the interbody bone implant illustrated in FIG. 1; and,

FIG. 5 is a first side view of the interbody bone implant illustrated in FIG. 1.

The broken-jagged lines which define the boundary of the claimed design do not form part of the claimed design. The broken lines are for environmental purposes only and form no part of the claimed design.

1 Claim, 2 Drawing Sheets
